STAMPED METAL FLUID HEATER

Albert P. Ball and William Marshall, Detroit,
Mich., assignors to Briggs Manufacturing Company,
Detroit, Mich., a corporation of Michigan

Application October 10, 1935, Serial No. 44,406

3 Claims. (Cl. 122—156)

The present invention relates to a fluid heater having a fluid-heating portion preferably formed from sheet metal stampings, the heater being particularly but not exclusively adapted for use 5 with a fluid storage tank of conventional design and is of a construction which may be used satisfactorily in installations for heating water for domestic uses.

It is an object of the present invention to 10 provide a fluid heater which has a high efficiency in heating fluids with which it is used, the heater being of a compact size and of economical construction, being of a construction which may be formed largely of sheet metal stampings.

15 It is a further object of the invention to provide a fluid heater which is so constructed of sheet metal stampings as to provide a substantially uniform circulation of the fluid at all points of contact with the heated surface and thus to increase the service life of such heater and to 20 effect the substantial elimination of deposits in the fluid chamber and the consequent burning out of the heated wall of the chamber.

Fluid heaters intended for similar uses heretofore known in the art have been provided with 25 metallic tubular coils through which was circulated the fluid to be heated. The coils were commonly of a relatively small cross-sectional area which remained uniform throughout the 30 length of the coil so that a constant velocity would normally be imparted to the fluid flowing through the coils. When, however, heat was supplied as in conventional practice to the lower portions of the coils, the fluid in the coils at that 35 point was heated to a greater degree than the fluid in the upper portions of the coils and the velocity of the fluid passing through the coils was greatly increased so that the rate of flow of fluid through the coils at points removed from 40 the point of application of greatest heat was so rapid as to prevent substantially uniform heating of the fluid while in the heater. In addition to the high cost incident to the formation of heating coils used in such heaters, it is well known 45 that the coils become lined with various mineral substances carried by the fluid to be heated. For example, in the case of hot water heaters it is common to find upon opening such coils a relatively thick coating of mineral carbonates and 50 the like on coils at the points of greatest application of heat to the fluid. This coating of mineral carbonates not only reduces the efficiency of the heater, but also impairs the free circulation of fluid through the heater and, if allowed to 55 accumulate over a period of time, results in either

plugging the coils or causing a breakage of the coils by reason of the high pressures built up therein by the fluid which cannot circulate freely through the coils.

The foregoing defects of prior existing structures are overcome by the present invention which in one preferred embodiment thereof is shown in the accompanying drawings.

Other objects of this invention will appear in the following description and appended claims, 10 reference being had to the accompanying drawings forming a part of this specification wherein like reference characters designate corresponding parts in the several views.

Fig. 1 is a longitudinal sectional view showing 15 a heater of our present invention, showing a fragment of a stack pipe connected thereto.

Fig. 2 is a sectional view taken substantially on the line 2—2 of Fig. 1 in the direction of the arrows.

Fig. 3 is a sectional view taken substantially 20 on the line 3—3 of Fig. 1 in the direction of the arrows.

Fig. 4 is a sectional view taken substantially 25 on the line 4—4 of Fig. 1 in the direction of the arrows.

Fig. 5 is a sectional view taken substantially 30 on the line 5—5 of Fig. 1 in the direction of the arrows.

Fig. 6 is a sectional view taken substantially 35 on the line 6—6 of Fig. 1 in the direction of the arrows.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or 40 terminology employed herein is for the purpose of description and not of limitation, and it is not intended to limit the invention claimed herein beyond the requirements of the prior art.

Referring to the drawings, particularly to Fig. 45 1, the fluid heater of the present invention comprises a fluid jacket formed by joining the outer shell 10 with an inner shell 11 so as to provide a fluid receiving chamber 12 therebetween. As shown in Fig. 1, the fluid jacket on the exterior 50 is generally conical in shape, but the inner plate 11 is formed so as to determine the size and shape of the fluid receiving chamber 12 and is secured as by welding to the outer wall 10 adjacent each 55 of the ends thereof.

The outer jacket 10 and the inner jacket 11 are both formed preferably from flat sheet metal stock which is formed as by conventional stamping operations. As shown in Figs. 3, 4 and 5, the outer shell 10 is formed to provide an outer casting which tapers substantially uniformly throughout its length. The outer shell 10 is bent to provide longitudinally extending lugs 13 which project outwardly from the surface of the outer shell 10. The inner shell 11 is formed to provide a series of longitudinally extending corrugations 14 at portions thereof where the greatest amount of heat is supplied to the shell 11. The corrugations may be formed in the sheet metal as by conventional rolling or stamping operations. The inner shell 11 may be formed of any preferred type of sheet metal which has a relatively high efficiency in the transfer of heat from the interior of the heater to the fluid chamber 12 and which either is substantially non-corrosive with the fluid passing through the chamber or which has been treated so as to become substantially non-corrosive.

The provision of the corrugations 14 increases the surface area of the inner shell 11 which will come in contact with the heat and also in contact with the fluid medium circulating through the chamber 12. The inner chamber 11 is provided with longitudinally extending edges 15 which are turned and project outwardly to a point of contact with the flanges 13 provided on the outer shell 10. The flanges 13 and the edges 15 are secured as by welding. This construction provides a baffle 16 which extends longitudinally throughout the length of the fluid chamber 12 so that the fluid in the chamber 12 will be required to rise as a column instead of circulating as a flowing stream. This increases the efficiency of the heater in that it provides a more constant body of fluid to be heated than where the fluid is permitted to circulate as a flowing stream around the heating chamber.

At the points where the least amount of heat is supplied to the inner shell 11, the shell is formed, as shown in Fig. 3, without the longitudinal corrugations 14 in the surface thereof. The interior of the heater is thus formed to provide a central flue 20 surrounded by the inner shell 11 and through which the heated gaseous products of combustion are conveyed to the stack 21. In order to increase the surface area of contact of the heated gaseous products of combustion with the inner shell 11, a series of baffles 22 are interposed in the flue 20. As shown in Figs. 1 and 2, each of the baffle members 22 is secured to a depending rod 23 which is secured to a cross bar 24 placed adjacent the top of the shells 10 and 11. Each of the baffles 22, as shown in Figs. 1, 2, 3 and 4, comprises a circular disc 25 to which lugs 26 are secured which extend outwardly therefrom to contact with the inner shell 11. This contact assists in maintaining the baffles 22 in the central portion of the flue 20 and also serves to increase the amount of heat conveyed to the shell 11. Each of the circular portions 25 of the baffles 22 is stamped or otherwise formed to provide a conical surface 27 having its apex lying in a line extending through the rod 23 and pointing downwardly toward the lower portion of the flue 20. The provision of the conical surface 27 on each of the baffles 22 serve to deflect outwardly toward the inner shell 11 the heated gaseous products of combustion which travel upwardly through the flue 20.

The particular form of the fluid heater here-

in shown may be varied in its construction in such a manner as to accommodate various types of heating apparatus. One preferred type of heating apparatus which is shown herein utilizes combustible gas as the fuel and admixes such gas with air and is distributed through a burner 30 which is provided with a series of jets 31. When, as here shown, the heater of the present invention is adapted to this type of heating apparatus, a stamped shell is provided to form a chamber in which the burner 30 is placed. One form of such shell is shown in Fig. 1 and comprises an annular band or collar 32, the upper edge of which telescopes inside the lower end of the inner shell 11.

In order to permit access to the interior of the chamber surrounded by the collar 32, a portion of the collar 32 is cut away and a hinged door 33 is provided. As shown in Fig. 6, the hinged door 33 may be formed from sheet metal and pivoted about a rod 34 which is secured in the collar 32 adjacent one vertical edge of the opening provided therein. A door 33 may be maintained in a closed position by a friction catch utilizing the resiliency of the metal used in forming the door. Such a catch may be formed by the provision of a depressed portion 35 on the inner surface of the door 33 which engages an outwardly extending member 36 formed in the collar 32 at a point adjacent one vertical edge of the opening provided therein. In order to facilitate the opening and closing of the door 33, an extending handle 37 may be provided thereon.

The burner 30 may be maintained in the chamber by means of a burner supporting base member 40 provided with upwardly extending end portions 41 which telescope inside the lower edge of the collar 32 and are secured thereto as by welding or the like. The base member 40 is provided with tapering sides 42 and a flat portion 43 in which a burner receiving opening 44 is provided (see Fig. 6). The burner 30 is supported on a stem 45 on which an annular shoulder 46 is provided. The stem 45 is also provided with a screw-threaded portion 47. The stem 45 extends upwardly through the opening 44 and is clamped thereon as by nuts 48 which engage with the screw-threaded portion 47 on each side of the flat portion 43 of the supporting member 40. The stem 45 is connected with a source of gas supply (not shown) and is provided with an interior conduit 49 for supplying gas to the interior of the burner 30.

Fluid to be heated is supplied to the fluid chamber 12 through an intake coupling 50 which is connected to the outer shell 10 at a point adjacent the lower end thereof. The fluid then passes to the chamber 12 but is prevented from flowing as a stream therein by reason of the longitudinal baffle 16 and the fluid rises as a column in the chamber 12 and is discharged through the discharge coupling 51 which is secured to the outer shell 10 at a point adjacent the upper end thereof.

In order to insure substantially uniform heating of the column of fluid in the chamber 12, the construction herein shown provides an interior chamber 12 of gradually decreasing capacity so that the greatest volume of fluid is in the lower part of the chamber and comes in contact with the greatest amount of heat. As the fluid in the lower portion of the chamber is heated and rises in the chamber 12, it moves toward the discharge coupling 51 in the form of a gradually thinning annular band which absorbs the

heat which passes through the inner shell 11 at the point adjacent the top thereof. The heat at this point, however, is of considerably less intensity than the heat supplied at the lower 5 end of the chamber as the heated products of combustion have been cooled by repeated contacts with the heat contacting wall of the inner shell 11. It has been found that this construction of the fluid heating chamber 12 is desirable as 10 it tends to maintain the flow of fluid through the heater at a substantially constant velocity and thus to provide a substantially uniform transfer of heat from the heated products of combustion to the fluid during its travel through the 15 heating chamber.

What is claimed is:

1. A fluid heater comprising a boiler formed of inner and outer sheet metal stampings having fluid inlet and outlet ports and having a flue 20 extending longitudinally of the interior thereof, said inner stamping providing a flue lining member forming one wall of said boiler and having longitudinal corrugations to increase its surface contact with gases in said flue and the fluid in 25 said boiler, and said inner stamping having a pair of longitudinally extending cooperating flanges projecting outwardly in flatwise abutting relation into contact with and secured to said outer stamping to provide a longitudinal 30 baffle for the boiler, and a heating member dis-

posed adjacent said flue and adapted to discharge heated products of combustion therethrough.

2. A fluid heater comprising spaced inner and outer shells secured together to provide a fluid chamber therebetween, a heating member secured adjacent said inner shell, and a fluid inlet and fluid outlet communicating with said chamber, the inner of said shells comprising a sheet metal plate corrugated longitudinally thereof to increase the surface area exposed to contact with the fluid in said fluid chamber and folded to provide extending portions attached to said outer shell, thereby to provide a baffle extending longitudinally of said fluid chamber.

3. A fluid heater including spaced inner and outer shells sealed to provide a fluid chamber therebetween, a fluid inlet and fluid outlet communicating with said chamber, the inner of said shells comprising a sheet metal plate corrugated 20 longitudinally thereof to increase the surface area exposed to contact with the fluid and folded to provide extending portions attached to said outer shell to form a baffle extending longitudinally of said fluid chamber adapted to break 25 up the fluid stream flowing inwardly into said chamber from said fluid inlet.

ALBERT P. BALL.
